UNITED STATES PATENT OFFICE.

CONSTANTINE APPELHOFF, OF DAYTON, OHIO.

OUTLET STRAINER.

Application filed December 27, 1919. Serial No. 347,693.

To all whom it may concern:

Be it known that I, CONSTANTINE APPELHOFF, a citizen of the United States, residing at Dayton, in the county of Montgomery and State of Ohio, have invented certain new and useful Improvements in Outlet Strainers, of which the following is a specification.

My invention relates to improvements in plumbing fittings and especially to an outlet drainer for wash bowls, bath tubs, laundry trays, and sinks.

The object of the invention is to simplify the structure as well as the means and mode of operation of such strainers whereby they will not only be cheapened in construction, but will be more efficient in use, capable of being securely locked in engagement in the drain, easily and quickly applied and removed, and unlikely to get out of repair.

A further object of the invention is to provide a removable strainer and improved locking means therefor, by which the strainer may be readily engaged in the outlet passage, and which will be more or less universal in its adjustment to different styles of outlet fittings.

With the above primary and other incidental objects in view as will more fully appear in the specification, the invention consists of the features of construction, the parts and combinations thereof, and the mode of operation, or their equivalents, as hereinafter described and set forth in the claims.

Referring to the drawings, Fig. 1 is a sectional view of a portion of a wash bowl and the outlet therefor, to which the present invention has been applied. Fig. 2 is a detail sectional view of one embodiment of the strainer forming the subject matter hereof removed from the outlet fitting. Fig. 3 is a bottom sectional plan view of the outlet fitting and inserted strainer taken on line 3—3 of Fig. 1. Fig. 4 is a detail view of one of the retaining catches of the construction shown in Figs. 1 to 5 inclusive. Fig. 5 is a detail sectional view of a modification of the strainer embodying an adjustable detent or locking device. Fig. 6 is a side elevation of a further modification of the locking or detent means. Fig. 7 shows a clamp collar for the screen.

Like parts are indicated by similar characters of reference throughout the several views.

Much of the difficulty experienced with household or other plumbing is due to the clogging of waste pipes by foreign material. This is particularly true in hotels or 60 public institutions and buildings, where matches, chewing gum, bits of paper and other débris are frequently thrown into wash bowls or sinks. The difficulty is further aggravated by the lodgment of small 65 pieces of soap, hair, lint, and ravelings in the outlet conduits of laundry trays, bath tubs and wash stands. This difficulty is sought to be overcome by the present construction, wherein a strainer member is 70 removably locked within the outlet fitting. This strainer is adapted to intercept and hold waste material and débris which might otherwise clog the outlet passage, and upon disengagement from the outlet fitting, the 75 strainer may be easily and conveniently emptied and cleaned.

Referring to the drawings, 1 is an ordinary wash bowl construction, having the usual overflow orifice 2, leading to the outlet fitting 3. The outlet fitting 3 comprises a tubular sleeve having a flange or collar 4 at its inner or upper end for engagement with the bottom of the wash bowl 1. The sleeve 3 is screw threaded upon its exterior 80 for the engagement of the locking or clamp nut 5, and the attachment of the offtake conduit. As ordinarily constructed the fitting 3 is provided with oppositely disposed orifices 6, which register with the overflow conduit leading from the outlet 2. The outlet fitting 3 is normally closed by the insertion of a stopper or plug 7, this is the usual drain connection for wash stands, bath tubs, 85 and laundry trays, and per se, forms no part 90 of the present invention.

The strainer element forming the subject matter hereof comprises a flanged collar 8, which supports a pendant basket or strainer body 9. The strainer 9 may be of 100 screen or wire mesh or may be of perforated sheet metal as shown in Fig. 6. The strainer is of such size and proportions as to fit snugly within the outlet fitting 3, with the horizontal flange of the collar 8 overlying the flange 4 of the fitting. A gasket 10 of rubber or other packing material is preferably though not necessarily fitted between the horizontal flange of the collar 8 and the like flange 4 of the fitting 3. While 11 the screen member fits snugly within the fitting it is easily insertable into and remov-

able therefrom. The strainer basket 9 whether of wire mesh fabric or of perforated sheet metal of such length as to extend to the bottom of the lateral opening 6, or preferably somewhat therebelow, in the drawings has been shown as extending approximately to the cross bar or baffle, ordinarily found in the fittings 3. This baffle or cross bar 11 is intended for somewhat the same purpose but is ineffective for stopping small particles, or such material as lint, ravelings and hair which in fact cause most of the plumber's trouble.

For the purpose of detachably engaging the strainer member within the fitting 3 there are attached to the inside of the flanged collar 8 at diametrically opposite points, spring fingers 12. These spring fingers 12 are riveted, soldered, or brazed, or otherwise fixedly attached to the collar 8 at the point 13, and the ends of such fingers are out-turned and project radially beyond the collar 8, thru slots 14 therein. The outward protruding ends 15 of these fingers 12 are preferably though not necessarily somewhat beveled as shown in Fig. 4 to afford a slight cam action which tends to draw the strainer firmly to its seat. The ends 15 of the retaining finger 12 when projected outward engage beneath the upper edges of the lateral opening 6 in the fitting 3, as shown particularly in Figs. 1 and 3, thereby holding the strainer in place, and preventing it being withdrawn with the stopper or plug 7. To detach the strainer, it is an easy matter to insert the finger within the outlet orifice or to employ a sharp instrument to spring the fingers 12 inward, thereby withdrawing the protruding end 15 thereof, from beneath the edge of the opening 6.

Inasmuch as there is a slight variation in the spacing of the upper edges of the lateral opening 6 from the flange 4, of the outlet fittings of different manufacture, there has been shown in Fig. 5 a modification having a universal adjustment to enable its use upon outlet fittings of different proportions. In this construction the retaining finger instead of being fixedly attached as in Figs. 1, 2, and 3, is vertically adjustable within the flange collar 8. To this end the flange collar is indented as at 16 to form an inward projecting arch tongue or loop beneath which the one end of the retaining finger 12' projects. The indented or arched portion 16 of the collar 8 is provided with a vertical slot 17 in which engages a stud 18 carried by the retaining finger 12'. The opposite out turned end of the retaining finger 12' projects outwardly thru an elongated slot or opening 20, one side of which is serrated to form a series of rests or stops for the finger 12'. The finger 12' may be adjusted vertically within the flange collar 8 by sliding one end in the slot 17, and by engaging the

opposite end upon any one of the series of teeth or serrations 21 to accommodate the device to different outlet fittings 3. Other than the features of universal adjustment the construction and function is as before described. In Fig. 6 there is shown a further modification in which a series of tongues 22 are projected outwardly from the material forming the flange collar 8 at different heights therein. For convenience the tongues are preferably arranged in a spiral series. The strainer device will be held in engagement with the fitting 3, by the interlocking of any one of the integral tongues 22, beneath the upper edge of the openings 6. To disengage this form of lock, the strainer is rotated thru a quarter revolution to bring the projecting tongues 22 into registry with the solid portion of the fitting 3, intermediate the opening 6, whereupon the strainer may be lifted from the fitting. It will be understood that this rotation can be effected only in the direction of the attached ends of the tongues.

While the perforated sheet metal strainer construction has been shown in the drawings in conjunction with the last mentioned form of interlocking means it will be understood that the wire mesh fabric construction may be utilized with the integral locking tongue construction or the perforated sheet metal strainer may be utilized with the locking construction shown in Figs. 2 and 5.

As thus described there is provided a strainer basket having an outwardly projecting flange collar which rests upon a top of the outlet fitting, and which is provided with locking detents for fixedly engaging it with such fitting, but which permits the detachment therefrom.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. The combination with an outlet drain

- fitting of a substantially cylindrical strainer basket extending within the outlet, a peripheral flanged collar thereon overhanging the end of the outlet fitting, and a spring arm 5 within said strainer basket, the extremity of which is extended through the side of said basket and into engagement with said fitting for releasably engaging the strainer basket with the outlet fitting.
- 10 2. The combination with a receptacle having an outlet orifice of a strainer basket projecting within such outlet, a peripheral flange carried by the basket and overhanging the bottom of the receptacle adjacent to the 15 outlet orifice, and a spring actuated detent operable from the interior of said strainer basket and extending peripherally therebeyond for detachably engaging the strainer basket in the outlet orifice.
- 20 3. The combination with a drain fitting having a lateral opening therein, of a strainer unit to be removably inserted in the mouth of said strainer fitting in a position overlying the lateral opening, and radially 25 extending detent means carried by the strainer unit for engagement in the lateral opening of the fitting.
4. In a device of the character described, a strainer basket adapted to be removably 30 inserted within the outlet orifice of a receptacle and depressible detent means projecting radially from the peripheral wall of the basket and engaging within the outlet of the receptacle.
- 25 5. In a device of the character described, a strainer basket insertable within the outlet orifice of a receptacle, and a spring finger secured to the interior wall of the basket, the end of said finger being out turned and 40 through the wall of the basket for engagement with a supporting structure.
6. In a device of the character described, a strainer basket insertable within the outlet orifice of a receptacle, and a cam detent carried thereby for engagement with a supporting 45 structure, the engagement of which by said cam detent tends to draw the strainer basket to its proper position.
7. In a device of the character described, a strainer basket insertable within the outlet orifice of a receptacle, and vertically adjustable detent means carried thereby adapted to lock the strainer basket in its adjusted position.
8. In a device of the character described, a strainer basket having a slot in the side wall thereof, and a detent projecting outwardly through said slot and adjustable to different operative positions therein.
9. In a device of the character described, a strainer basket insertable within the outlet orifice of a receptacle, having a slot in the side wall thereof, the edge of said slot being serrated, and an adjustable detent capable of engagement with any one of said serrations.
10. In a device of the character described, a strainer basket, a detent slidably engaged therewith for vertical adjustment, and a series of stops in the path of adjustment of the detent with any one of which the detent may be engaged.
11. In a device of the character described, a cup shaped strainer basket, having an angularly disposed peripheral flange substantially coincident with the edge of the basket and yielding detent fingers projecting laterally from the side walls of the cup shaped basket for detachably locking said flanged basket within the outlet orifice of a receptacle, said yielding detent fingers being manually retractable from the interior of the basket.
12. The combination with a tubular outlet fitting having a lateral drain orifice, of a strainer basket insertable within the tubular fitting and overhanging the lateral orifice thereof and a manually retractable detent carried by the basket detachably engageable within the lateral drain orifice thereof.
- In testimony whereof, I have hereunto set my hand this 17th day of December, A. D. 1919.
